GRILLE MATERIAL

Judson E. Fuller, River Forest, Ill., assignor to The Harrington & King Perforating Co., Inc., Chicago, Ill., a corporation of Illinois

Filed Apr. 6, 1967, Ser. No. 6,544

Term of patent 14 years

(Cl. D54—2)

FIG. 1 is a front view of a corner portion of a grille material showing my new design, the balance of the material being like that shown;

FIG. 2 is a cross-sectional view taken at the line 2—2 of FIG. 1;

FIG. 3 is a cross-sectional view taken at the line 3—3 of FIG. 1, and

FIG. 4 is a cross-sectional view taken at the line 4—4 of FIG. 1.

I claim:

The ornamental design for a grille material, substantially as shown and described.
